FREDERICK C. GOLDENBAUM, OF KEARNY, NEW JERSEY, ASSIGNOR TO INTERNATIONAL PRINTING PLATE COMPANY, INC., OF NEW YORK, N. Y., A CORPORATION OF NEW YORK.

METHOD OF FORMING CELLULOID PRINTING PLATES.

1,422,695.

Specification of Letters Patent.

Patented July 11, 1922.

Application filed August 31, 1920. Serial No. 407,280.

To all whom it may concern:

Be it known that I, FREDERICK C. GOLDENBAUM, a citizen of the United States, residing at Kearny, county of Hudson, and State 5 of New Jersey, have invented certain new and useful Improvements in a Method of Forming Celluloid Printing Plates, of which the following is a specification.

My invention relates generally to printing plates and more particularly to improvements in the method of forming celluloid plates described in the patent to Ludwig 747,738, Dec. 22, 1913.

In manufacturing celluloid printing plates 15 according to the method referred to, I have found that the use of unyielding material such as steel or other metal as a die member for forcing the celluloid into engagement with the face of the lead mold gives very 20 imperfect results because of the failure of the rigid forcing die member to adapt itself to variations in the thickness of the celluloid. I have avoided this by making use of loose pads of felt arranged to directly receive and apply the pressure of the forcing 25 die to the celluloid which was interposed between the felt pad and the operative face of the heated lead mold. This method, while largely overcoming the objectionable 30 features arising out of the use of an unyielding forcing die member, was still open to the objection that interstices in the surface of even the fine quality of felt employed would occasionally permit of the failure to 35 press a minute portion of the celluloid into the face of the mold with a consequent loss of a corresponding microscopic detail in the finished plate.

I have discovered that I can overcome the 40 objections referred to and, as a result, obtain celluloid printing plates in which the finest details of the design carried by the mold are faithfully reproduced in the celluloid. I accomplish this by placing between 45 the felt pad and the thin sheet of celluloid on which the impression is to be made a second supplemental sheet of celluloid which serves to transmit from the felt pad to every portion of the area of the sheet in contact 50 with the mold a uniform pressure that forces the sheet into contact with every minute detail of the design formed in the mold surface.

In the drawing the single diagrammatic

view shown illustrates a preferred form of 55 apparatus for carrying out the method embodying the present invention.

Referring to the drawing, there is shown at 1 the stationary bed plate of a suitable hydraulic press of which the member 2 represents the vertically reciprocable forcing member or die head. At 3 is shown a removable die plate which, together with the lead matrix or mold member 4, is heated in any suitable heating device, not shown, 60 to a temperature such as will reduce to a desired condition of plasticity a sheet of celluloid 5 when the sheet is pressed against the upper surface of the lead plate 4 on which the design to be reproduced appears. 70

In order to avoid the use of the unyielding surface of the die head 2 with the celluloid and a resulting imperfect impression and possible rupture and distortion of the sheet, I make use of the felt cushion 6 which 75 is placed in an intervening position between the die head 2 and the celluloid sheet, as has been already described.

A still more important feature of the invention resides in the placing of a supplemental sheet of celluloid 7 between the cushion 6 and the impression-receiving sheet 5. The supplemental transfer or cushion sheet 7 serves to absorb the surface irregularities of the felt pad and to transmit uniformly to every portion of the sheet 5 the pressure exerted by the die head 2, with the result that every fine detail of the design on the face of the mold member 4 is accurately reproduced on the surface of the 90 sheet 5.

The plate 5 is retained under pressure for a sufficient time to permit the temperature of the die 3 and mold 4 engaged thereby to fall below the temperature of plasticity of 95 the celluloid when, the celluloid plate 5 having become hardened into its permanent condition is removed and mounted on a suitable block for use as a printing element.

It will be noted that the various members 100 of my pressure applying apparatus are wholly unattached from each other so that they can be readily transferred from a suitable assembly table to the heating device and to the pressure applying means as desired. 105 In practice I find it convenient to reverse the position of the transfer sheet 7 for each operation, the same sheet being used over

and over again for a great many plate forming operations.

While I have referred to the product obtained by the described method as a printing plate, it will be clear that other analogous products, such as sound records, may also be secured by the carrying out of the method set forth.

I claim—

10 1. That method of forming a printing plate which consists in pressing a body of material rendered plastic by heat, between a mold heated to a temperature sufficient to render the material plastic, and a yieldable body of similar material.

15 2. That method of forming a printing plate which consists in pressing a sheet of material rendered plastic by heat, together with a supplemental cushion sheet between a mold heated to a temperature sufficient to render the material plastic, and a cushioning member.

20 3. That method of forming a printing plate which consists in pressing a sheet of celluloid between a lead mold heated to a temperature sufficient to render the celluloid plastic, and a felt cushioning member.

25 4. That method of forming a printing plate which consists in pressing a sheet of celluloid between a lead mold heated to a 30 temperature sufficient to render the celluloid plastic, and a yieldable sheet of similar material.

30 5. That method of forming a printing plate which consists in pressing a sheet of celluloid together with a supplemental cushioning sheet of celluloid between a lead mold heated to a temperature sufficient to render the celluloid plastic, and a cushioning member.

35 6. That method of forming a printing plate which consists in pressing together a heated die plate, a heated lead mold, an impression-receiving sheet of celluloid, a cushioning sheet of celluloid, and a felt pad arranged in the order named, in cooling and 40 disassembling said parts, and in removing the impressed sheets from contact with said mold.

45 Signed at Arlington, in the county of Hudson, and State of New Jersey, this 28th day of July, 1920.

FREDERICK C. GOLDENBAUM.
